United States Patent Office

Des. 182,858

Patented May 20, 1958

182,858

FONT OF TYPE

Edward W. Spector, Newark, and Oscar Lunden, East Orange, N. J., assignors to Beneficial Finance Co., Wilmington, Del., a corporation of Delaware

Application August 8, 1957, Serial No. 47,265

Term of patent 14 years

(Cl. D64—12)

The figure on the drawing is a plan view of a font of type showing our new design.

We claim:

The ornamental design for a font of type, substantially as shown.
